AMPLIFIER

Ira G. Wilson, New York, N. Y., assignor to Bell Telephone Laboratories, Incorporated, New York, N. Y., a corporation of New York

Original application May 27, 1936, Serial No. 82,156. Divided and this application September 8, 1938, Serial No. 228,987

3 Claims. (Cl. 179—171)

The present invention relates to improvements in amplifiers and more particularly to a power supply for a number of amplifiers such as are operated continuously.

This application is a division of a copending application Serial No. 82,156, filed May 27, 1936, for Amplifiers, now U. S. Patent No. 2,191,167, Feb. 20, 1940.

An object of the invention is the provision of a single battery for use with a large number of amplifiers for both filament lighting and for plate voltage without resulting irregularities in the drain and without undue coupling or cross-talk between amplifiers supplied by the same battery.

Further objects and advantages of this invention will appear from consideration of this specification and accompanying drawing illustrative of a typical embodiment of the invention in which the single figure shows a single power source, used both for filament lighting and for plate current, the full voltage of which is employed for plate voltage and successive sections of which are tapped for filament lighting for separate repeater amplifiers.

The drawing shows schematically a group of amplifiers A, B and C to N, each amplifier being associated with a communication circuit or telephone pair, of which a large number are employed, for example, in a lead covered cable in a carrier telephone system. The circuits may be open-wire pairs, radio circuits or any suitable medium as well as those of a lead covered telephone cable or the like. The amplifier A is associated with one of the circuits or pairs 9 through an input transformer 10 having suitable shielding. The secondary winding of the transformer 10 is connected in this case to the control grid of a power pentode 11 of the type known as 310-A Western Electric pentode tube. The gain of the amplifier is controlled at 12 by some suitable means not shown in detail for varying impedance in shunt of the circuit connecting the input to the output bridge 15. The tube itself is self-biased by resistance 13 in shunt with a condenser 14.

The amplifier A of itself forms no part of the present invention and will not be described in all its details. It is chosen for illustration because it represents a type of repeater to which the power supply circuits of the invention are well adapted. For information as to structure and performance of a repeater of generally similar type, reference may be made to the H. S. 55

Black U. S. Patent No. 1,956,547, granted May 1, 1934.

The tube 11 is connected to a succeeding amplifying tube 19 through an interstage network 5 as shown. The plate voltage and the positive screen grid voltage of the tubes 11 and 19 are fed by the same plate battery 20 through the usual connecting impedance elements from lead 40. The second amplifying tube 19 is connected 10 to an output or power tube 24 through an interstage network similar to that preceding the tube 19. The output or power tube 24 is a 311-A Western Electric power amplifier pentode. The plate of the power amplifying pentode is 15 connected to the positive pole of the plate battery through lead 40 in series with an inductance 25 and through the customary primary winding of the output transformer. The cathode of the power tube is connected to the negative side of 20 the plate supply battery and to ground through an inductance 27. In shunt therewith is a condenser 28 furnishing an alternating current bypass to ground.

The battery 20 employed for both filament 25 lighting and plate voltage supply is a single storage battery of about 150 volts subdivided by taps into n , in this case, seven sections, a , b , c , etc. The amplifier A has its filaments lighted from section a . The amplifier B has its filaments lighted from section b of the battery and so on while the eighth amplifier at a repeater station has its filaments lighted from the first section a of the battery, the ninth from section b , and so on.

Where the number of amplifiers at a station is 30 less than the number of sections in which the plate battery is divided, or is not an even multiple of such number, individual filament lighting 35 sections not heavily enough loaded may be loaded with dummy loads, such as leak resistances. The drain on the main supply battery 20 is thus kept uniform throughout its length and the usual practice may be followed of keeping the battery 40 on a uniform charge between its end terminals without the necessity for frequent attention to each individual cell to bring it up to normal charge.

It has been noted that the first two tubes of 50 the amplifier are self-biased. A suitable wet or dry biasing C battery 29 is furnished for the power amplifying pentode in ordinary manner.

The power supply system disclosed is not limited in application to telephone repeater service or to the use of either wet or dry battery supply.

What is claimed is:

1. In a repeater installation, a plurality of communication circuits, a plurality of amplifiers each including heater type tubes, one amplifier being individual to each circuit, a common battery for supplying both anode voltage and heater current for the tubes of said amplifiers, said battery having a negative pole connected in common to the cathodes of said tubes and a positive pole connected to the anodes of said tubes, a 10 heater circuit for the heaters of the first amplifier connected between the negative pole and an intermediate point in said battery and a heater circuit for another amplifier connected between said intermediate point and a more positive point 15 in said battery.

2. In a telephone system, a repeater station, a plurality of communication circuits at said station, an amplifier at said station for each of said circuits, each of said amplifiers embodying vacuum tubes, a single power source for all of said

amplifiers, said power source being tapped to provide a heating current circuit individual to each amplifier.

3. In a telephone system, a repeater station, a plurality of communication circuits at said station, a separate amplifier at said station for each of said circuits, each of said amplifiers including vacuum tubes, a common power source for supplying both anode voltage and cathode heating current, said source having a negative terminal connected in common to the cathodes of said tubes and a positive terminal connected in common to the anodes of said tubes, a cathode heating circuit for one amplifier connected between the negative terminal and an intermediate point in said source, and another heating circuit for a second amplifier connected between said intermediate point and a more positive point in said source.
